UNITED STATES PATENT OFFICE.

JAMES H. MAURER, OF HAMBURG, PENNSYLVANIA, ASSIGNOR OF TWO-THIRDS TO WILSON E. SCHMICK, OF SAME PLACE, AND GEORGE H. GERBER, OF POTTSVILLE, PENNSYLVANIA.

PACKING FOR VALVE-STEMS.

SPECIFICATION forming part of Letters Patent No. 611,386, dated September 27, 1898.

Application filed December 3, 1897. Serial No. 660,664. (No model.)

To all whom it may concern:

Be it known that I, JAMES H. MAURER, a citizen of the United States, residing at Hamburg, in the county of Berks and State of Pennsylvania, have invented certain new and useful Improvements in Packing for Valve-Stems; and I do hereby declare the following to be a full, clear, and exact description of the invention, such as will enable others skilled in the art to which it appertains to make and use the same.

My invention relates to packing for valve-stems, is designed to dispense with the stuffing-boxes and glands generally used to prevent leaking of fluids or liquids, and consists in certain improvements in construction, which will be fully disclosed in the following specification and claims.

In the accompanying drawings, which form part of this specification, Figure 1 represents a side elevation of a valve-case; Fig. 2, a vertical section of the same; Fig. 3, a transverse section of the valve-stem and packing on line 3 3, Fig. 2; Fig. 4, a like view on line 4 4; Fig. 5, a vertical section, partly in elevation; Fig. 6, a transverse section of the valve-stem; Fig. 7, a vertical section of a modified construction of the valve-stem, and Fig. 8 a plan view of the lower end of the same.

Reference being had to the drawings and the letters thereon, A indicates a valve-case, B the valve, and C the handle, which is secured to the valve-stem in the usual manner, and all of which may be of any approved form, as they constitute no part of my invention. The valve shown is of the type known to the trade as "radiator-valves" and is of the turning-plug variety. The valve-stem is cylindrical at a and non-cylindrical at b and at its lower end is bent at c at a right angle to the body of the stem, and the part c engages a slot d in the upper end of the valve B, as shown in Figs. 2 and 5, to turn the valve in the valve-case to regulate the flow of liquid or fluid.

D indicates the packing, which is made of rubber and may be molded on the valve-stem and secured to the non-cylindrical portion b, but is free to turn on the part a, and at the lower end of the cylindrical portion h of the packing which surrounds the valve-stem is

a flange e, which rests upon the upper end f of the valve-case and packs the joint between the valve-case and the cap g, while the escape of liquid or fluid around the valve-stem is prevented by its surrounding packing h.

The packing surrounding the valve-stem is inclosed by a casing E, extending from the cap g to the under side of the handle C, and the flange e is protected against excessive heat by a disk i, of asbestos or other non-conductor of heat, applied to the inner surface of the flange e and also secured in position by the cap g of the valve-case.

The upper portion of the packing surrounding the valve-stem is prevented from turning thereon by the non-cylindrical part b of the stem, while the lower portion is free, and in turning the valve this portion of the packing is twisted, as indicated at k in Fig. 5, while the flange e and the upper portion of the packing remain stationary.

It is obvious that other irregular forms may be substituted for the flat portion b of the valve-stem or that the stem may be cylindrical throughout its length, as shown at l in Fig. 7, a head m above it, to the lower end of which head and to the upper part of the cylindrical portion l adjacent to the head the tubular portion k of the packing is secured by "sweating" or by any other means to cause the packing to turn with the stem at its upper end, while the remaining portion is free to twist in turning the valve-stem, thereby permitting the packing to be molded upon a metallic core other than the valve-stem in the usual way of molding rubber articles and put on the market as an article of manufacture to be supplied to the trade.

On the lower end of this valve-stem is a plate n, having projections o o, Fig. 8, to engage the valve in place of the bent part c of the valve-stem.

Having thus fully described my invention, what I claim is—

1. A valve-stem provided with a flexible packing surrounding the stem, part of which is secured to the stem and part free and a flange at its inner end to engage the valve-case.
2. A valve-stem provided with a flexible

- packing surrounding the stem, secured to a part thereof, extending outside the body of the valve and having a flange at its inner end to engage the valve-case.
5. A valve-stem provided with a flexible packing, part being secured to the stem and having a flange at its inner end to engage the valve-case, and a heat-protector on the inner surface of the flange.
10. 4. A valve-stem having a portion thereof cylindrical and a portion non-cylindrical, in combination with a flexible packing surrounding said stem and provided with a flange at its inner end to engage the valve-case.
15. 5. A valve-stem having a portion thereof cylindrical and a portion non-cylindrical, in combination with a flexible packing secured to the non-cylindrical portion and free on the cylindrical portion and having a flange at its inner end to engage the valve-case.
20. 6. A valve-stem provided with a packing surrounding the stem, secured to a part thereof and having a flange at its inner end to engage the valve-case and the stem extending
- through the flange and constructed to engage 25 with a valve.
7. A valve-stem provided with flat and cylindrical portions, and a right-angled extension at one end, in combination with a packing surrounding the stem and having a flange 30 at its inner end to engage the valve-case.
8. A valve-stem provided with a packing surrounding the stem, part being secured thereto and having a flange at its inner end to engage the valve-case and a supplemental 35 casing extending from the body of the valve and inclosing said packing.
9. An article of manufacture, a packing for valve-stems consisting of an elongated cylindrical portion to surround the stem and 40 a flange at its inner end to pack the joint between the valve-casing and its cap.

In testimony whereof I affix my signature in presence of two witnesses.

JAMES H. MAURER.
